UNITED STATES PATENT OFFICE.

REINHOLD HERMAN, OF CRAFTON, PENNSYLVANIA.

FRAME STRUCTURE FOR BLUE-PRINTING APPARATUS.

942,175.

Specification of Letters Patent.

Patented Dec. 7, 1909.

Application filed January 18, 1909. Serial No. 472,846.

To all whom it may concern:

Be it known that I, REINHOLD HERMAN, a citizen of the United States of America, residing at Crafton, in the county of Allegheny and State of Pennsylvania, have invented certain new and useful Improvements in Frame Structures for Blue-Printing Apparatus, of which the following is a specification, reference being had therein to

10 the accompanying drawing.

My invention relates to improvements in blue-printing apparatus, and has particular relation to the frame structure thereof by means of which the various coöperating elements of the apparatus may be fixedly and accurately positioned to provide, with the supporting frame, a substantially unitary or self-contained apparatus. In apparatus of this type, it has generally been the practice to provide a supporting frame formed of separable members adjustably connected together, but generally removable for the purpose of providing for shipping, etc. The necessity for the separation of the parts for shipping and other purposes, requires, when the apparatus is to be again assembled, a re-adjustment of the parts to provide accurate movement and efficient service. As such assemblage of parts requires a high order of mechanical skill it is practically a requirement that the assembling be performed by a mechanic familiar with the apparatus, thus necessitating the supplying of a workman by the manufacturer for this purpose, thereby resulting in increased cost to the purchaser. In addition, the fact that there is a requirement of a great amount of adjustment of parts relative to each other prior to the shipment of the apparatus, and for testing purposes, places in the cost of manufacture the element of time involved in such nicety of adjustments with the result that the cost of the apparatus is increased to a considerable extent. Furthermore, the requirement of a frame capable of being taken apart for shipping purposes, necessitates the use of an excessive number of mechanical elements which, in themselves, owing to the fact that they must be secured to the various frames and attachments on the apparatus, form a weakness in structure physically and the additional fact that liability of misplacement of parts is present. For the purpose of overcoming

55 these objections, I provide a supporting structure which forms a rigid support for

all of the elements required in the apparatus, which requires but a minimum amount of adjustment of parts, and this adjustment is made permanently at the manufactory before shipment, the apparatus being assembled and tested prior to leaving the manufacturer and prepared for shipment in the condition in which it was placed during the testing operation, the consignee receiving the apparatus in such a condition as to require no action on his part, other than the removal of the crating etc., than to connect the lamp circuit with the source of electricity thereby eliminating all requirement of the attention of a mechanic subsequent to leaving the factory. These results are mainly due to the particular form of the frame employed in the apparatus, and my invention therefore has for its principal object the provision of a supporting frame for blue printing apparatus of a form and construction which will permit of a substantially rigid permanent connection of the operative parts of the apparatus.

A further object is to provide a frame of this character consisting of a minimum number of parts requiring but slight if any adjustment in assembling, which is durable in construction, of low cost of manufacture, and of a character capable of being interchangeable to provide for repairs, or for machines of various sizes.

A further object is to provide a novel support for the frame to prevent lateral swinging and to permit of adjustment for inequalities in the surface on which it is placed.

A further object is to provide a supporting frame for blue-printing apparatus adapted to serve as a support for a printing cylinder held stationary relative to the frame, or for a cylinder which may be rotated on a horizontal axis, or a frame which will permit of a rotation on a vertical axis, to permit access to the various surfaces of the printing cylinder where the apparatus is so positioned as to provide normally-inaccessible surfaces of the cylinder.

A further object of the invention is to provide a supporting-frame which will permit of the placing of the printing cylinder in position without requiring adjustments of the frame members, or the use of additional temporary bracing means.

To these and other ends, the nature of which will be understood as the invention is

hereinafter disclosed, my invention consists in the improved construction and combination of parts hereinafter fully described, illustrated in the accompanying drawings, 5 and particularly pointed out in the appended claims.

In the accompanying drawings, in which similar reference characters indicate similar parts in each of the views—Figure 1 is a 10 side elevation of the supporting frame of a blue printing apparatus and showing the printing cylinder in position thereon, said view also showing the lamp carried by the frame. Fig. 2 is a side elevation of the 15 same. Fig. 3 is a sectional view taken on line 3—3 of Fig. 1. Fig. 4 is a sectional view taken through one of the end-rings of the printing frame, and showing its position relative to the printing cylinder. Fig. 20 5 is a top plan view of the supporting frame at the point of juncture of the vertically extending bars, Fig. 6 is a diagrammatic view 25 of the supporting frame used with a printing frame rotatable on a horizontal axis, and Fig. 7 is a vertical section taken on line 7—7 of Fig. 3.

The main portion of the supporting-frame embodied in my invention comprises two bars 10, preferably angular in cross section, said bars being of a length sufficient to provide a vertically extending portion of greater length than the length of the printing frame, and a curved portion, designated as 11, the free ends of the curved portions of 30 the frame being brought into opposing contact midway between the planes of the two vertically-extending portions. While the curvature of the bars, is such that, when in position, the ends of the bars are located in 35 the position just described, said bars, as segregated elements, are substantial duplicates of each other, thereby requiring the formation of but a single type of bar for the frame.

To provide the bars against lateral movement when placed in position, I provide the lower end of each with laterally-extending 40 feet 12, the ends of which are adjustable, the adjustment being provided by suitable means such as a screw-threaded member having a 45 head threaded into an opening within the foot, the face of the head being adapted to contact with the floor, this structure being provided to secure a true vertical positioning of the bars where the surface on which 50 the apparatus is supported has inequalities which would prevent a normal positioning of the bars.

The curved ends of the bars 10, are 55 connected together by means of a casting 13, which extends over both of the bars and is secured thereto. The casting may, if desired, be formed with a bearing extending horizontally and having its axis extending at direct 60 right angles to the plane of the vertical por-

tions of the bars, said bearing being adapted to receive a shaft carrying sheaves for the lamp-cables, this construction providing a permanent positioning device for the lamp, and which requires no adjustment to provide an accurate centering of the lamp over 70 the printing frame and insuring a path of movement of the lamp exactly central of the printing-cylinder, and at the same time securing a proper positioning of the frame of the lamp relative to a normal path of travel 75 of the frame of the lamp in order that the lamp-frame will not provide blind portions at unexpected points within the printing cylinder.

The printing frame, shown in Figs. 1 and 2, comprises the printing cylinder and the end-rings, the latter being designated at 14. Said end rings are each preferably angular in cross section and providing portions extending in horizontal and vertical planes in proximity to the top and bottom edges of the glass sections of the printing cylinder, 85 said rings being cushioned relative to said sections by means of strips 15 of suitable 90 material, such as felt, preferably arranged as shown in Fig. 4.

The printing cylinder is composed of two semicylindrical glass sections of a combined circumferential length less than the circumferential length of the completed cylinder, the side edges of the sections being spaced apart by spacing bars 16, preferably formed of wood, each of said bars having its side edges provided with longitudinally extending recesses 17, each adapted to receive a cushioning means 18, such as felt, the particular arrangement of these parts being indicated in Fig. 3 of the drawings.

The end rings of the printing frame are 105 each provided on diametrically opposite sides with a casting 19 having an angular outwardly-extending portion 20, adapted to fit within the bars 10, said casting having a 110 normal width substantially equal to the width of the vertically-extending portion of the ring 14, and being elongated to provide a projecting portion 21 extending in the plane of the casting, said projecting portion forming a support for the bar 16, to 115 prevent a distortion of the cylinder, said castings being secured to the rings by suitable bolts and to the spacing bars by suitable screws. The outwardly extending portion 20 is preferably of a length to extend above 120 and below the plane of the edges of the ring 14, and each casting has its portion 20 provided with suitable openings adapted to register with openings within the bars 10 for the reception of suitable bolts when the 125 printing frame is completed.

From the above, it will be seen that the end rings of the printing frame perform a double function, viz: to serve as the end rings for the printing cylinder, and at the 130

same time as supporting members for the bars 10 to prevent a spreading movement of the bars, said rings, with the bars 10, forming a frame of extreme rigidity, permanent in character and substantially incapable of being moved to disturb the relative positions in which the parts are placed when the frame is assembled. Furthermore, the substantially-integral relationship existing between these members, when assembled, provides a rigid structure supported on the floor at spaced points, between which points the printing-cylinder is located, the latter serving as a weighting means for the structure sufficient to overcome the weight of the operating parts carried by one of the bars 10, thereby rendering the frame stable under all conditions of operation.

An additional advantage lies in the fact that the sheaves for the lamp cable are located on an integral portion of the frame, requiring no adjustment of parts for positioning the lamp. And the fact that the particular arrangement of the frame permits of a quick and accurate assembling of the printing cylinder within the printing frame is a great advantage, which will be understood from the following description of the manner of assembling the cylinder as heretofore practiced, and the manner in which the assembling is provided in the present structure.

Where the end rings of the printing frame are not secured to the supporting frame, it is necessary to construct the printing frame at a point distant from its operative position within the frame. In such case, the bottom ring is first placed on a suitable support, and the upper ring entirely removed from the connecting bars for the rings and laid to one side. The lower ring is then packed, after which the glass sections and spacing bars (where such are used) are placed on end within the lower ring. To retain the cylinder in its proper position while fitting and positioning the upper ring, the cylinder must be supported by a suitable spreader temporarily placed in position therein, after which the packing is placed in position and the ring placed on the upper end of the cylinder and adjusted to permit engagement of the ring and the connections for the two rings. The printing frame is then placed in its position within the supporting frame. To apply the printing cylinder in the frame herein disclosed, a different operation is required. Having the rings and bars 10 at hand, the lower end ring is secured in its permanent position in the bars 10, the upper ring being placed between the bars before securing the lower ring in position, the upper ring, however, being located a short distance above its normal position, and temporarily secured

therein by a single bolt; for instance, the ring may be moved upwardly from its normal position a distance sufficient to place one of the lower openings of its castings in alignment with the openings in the bars intended for the upper securing bolts when the ring is permanently positioned, and while in this position by a bolt. This places the upper ring in a position parallel and in vertical alignment with its normal position, and at the same time provides its normal effect of retaining the supporting bars against movement under weight of the printing cylinder. To permit this movement of the upper ring, the vertical portion of the bar 10 extends above the normal plane of the upper ring. The printing cylinder is then placed in position in the lower ring, the supporting bolts for the upper ring removed, and said upper ring lowered into its proper position at the upper end of the cylinder, and secured in its permanent position. It will therefore be understood that there is no requirement of the use of any temporary retaining structures for the cylinder during assembling of the printing frame; that the printing cylinder can be assembled in its frame while the end portions of the printing frame (the end rings) are in close approximation of their permanent positions without necessitating the movement of any part excepting the upper ring and this ring only in a direction axially of the cylinder, and with the castings in their proper alignment so as to require no adjustment in a horizontal plane to permit the ring being secured to the supporting frame; that although the printing cylinder is actually assembled with its lower end spaced from the floor, its weight will not tend to disturb the normal position of the vertical bars, since the latter are braced in opposition by the upper ring; and that the permanent positioning of the rings against a movement in a horizontal plane permits of the positioning of the elements of the printing cylinder, in assembling, so as to place the "blind" portions of the cylinder in their proper positions to coincide with the path of movement of the frame of the lamp when the apparatus is assembled, by placing the spacing bars 16 in diametrical alignment with the opposing bars 10, the particular positioning of the sheaves for the lamp-cable, as heretofore pointed out, insuring that the frame of the lamp will be in the same diametrical alignment during the path of travel of the lamp within the printing cylinder.

Another feature of this construction lies in the fact that the same frame may be used in connection with the construction of apparatus having printing-cylinders of different length, it being necessary only to provide a different position for the bolt openings for

the upper ring in the bars 10, the remaining structure being the same with an apparatus having the printing cylinder of any desired length.

- 5 The sheaves over which the lamp-cables pass (and which form the positioning means for the lamp axially of the printing-cylinder) are designated as 22; the lamp cables 23, and the lamp 24.
- 10 When the frame is to be used in connection with a printing cylinder having a rotatory movement on a horizontal axis, such as is shown in Letters-Patent No. 777,096, heretofore granted to me, but slight modifications need be made, these consisting in using but one bar 10 of complete length, the other bar extending upwardly from the floor a distance slightly greater than required to form the bearing for the trunnion of the 20 printing-frame; forming or securing trunnion-bearings to the bars, and connecting the lower ends of the bars together by the lower end ring, said ring, however, in this arrangement, not forming a portion of the 25 printing frame, but acting as a connecting member for the frames. The frame is braced by forming the trunnions and bearings therefor of a type which will prevent their relative axial movement. The remaining 30 portions of the apparatus are the same, the casting 13 and sheaves 22 being provided as in the structure heretofore referred to.
- To provide a printing-cylinder capable of being rotated on a vertical axis, to enable 35 the apparatus to be stationed in the corner of a room and be moved to permit access to all portions of the cylinder, it is necessary only to place suitable rollers on the feet 12 and the lower ends of bars 10, thereby permitting 40 the entire apparatus to be moved to provide the result obtained by the use of a cylinder having a rotative movement on a vertical axis.
- It will now be understood that with either 45 form of apparatus, the supporting frame is substantially the same, and that such frame serves to support all of the mechanisms required in the apparatus. As heretofore pointed out, the parts which heretofore have 50 required considerable time in adjusting to their proper positions, have predetermined positions in which they are placed in the assembling of the mechanism and which require no adjustment; after the apparatus is 55 assembled at the factory for testing purposes, the adjustments are complete and in proper form to be used by the consignee. After testing, the entire apparatus is crated (with the lamp properly positioned therein 60 and braced and secured) and shipment made. When received by the consignee, it is necessary only to remove the crating, attach the connections for the source of electricity to the proper binding posts and the apparatus 65 is ready for operation without adjust-

ment, unless parts should be broken *en route*, and this would be generally avoided by the form of crating or boxing, the particular form and arrangement of the frame permitting this to be done.

Having now described my invention, what I claim as new is:

1. In a blue-printing apparatus, a supporting frame comprising two spaced bars, and a printing frame between said bars, 75 said printing frame having an end ring positioned by and adjustably secured on said bars.

2. In a blue-printing apparatus, a supporting frame comprising two spaced bars, 80 and a printing frame between said bars, said printing frame having an end ring positioned by and adjustably secured on said bars, said ring and bars being complementally formed to permit said adjustments in 85 directions axially of the ring.

3. In a blue-printing apparatus, a supporting frame comprising two spacer bars angular in cross-section and connected together intermediate their ends, and a casting 90 carried by said frame and having a face seated on and secured to the angle of one of said bars to prevent torsional movements thereof, said casting having lamp-positioning means.

4. In a blue-printing apparatus, a supporting-frame comprising two spaced bars connected together at their upper ends, and a printing frame between said bars, said bars being positioned relatively to each other intermediate the end-planes of the printing-frame, one of said bars carrying a permanently-positioned means for supporting the lamp.

5. In a blue-printing apparatus, a supporting-frame comprising two spaced vertically-extending bars, and two spaced rings carried by and fixedly connected to said frame, said rings having their axes extending in parallelism with the spaced bars, said 110 rings forming the end-rings of the printing frame.

6. In a blue-printing apparatus, a supporting-frame comprising two spaced vertically-extending bars, and two spaced rings 115 carried by and fixedly-connected to said frame, said rings forming the end-rings of the printing frame, said bars being angular in cross-section, said rings extending within the angles of the bars.

7. In a blue-printing apparatus, a supporting-frame comprising two spaced vertically-extending bars, and two spaced rings carried by and fixedly-connected to said frame, said rings forming the end-rings of the printing frame, said bars being angular in cross section, said rings extending within the angle of the bars and having securing portions for complementally engaging said bars.

8. In a blue-printing apparatus, a supporting-frame comprising two spaced vertically-extending bars, and two spaced rings carried by and fixedly-connected to said frame, said rings forming the end-rings of the printing frame, said bars being angular in cross-section, said rings having castings provided with bar-engaging faces formed complementally to the inner faces of the bars.
9. In a blue-printing apparatus, a supporting-frame comprising two spaced vertically-extending bars, and two spaced rings carried by and fixedly-connected to said frame, said rings forming the end-rings of the printing frame, said bars and rings being angular in cross-section.
10. In a blue-printing apparatus, a supporting-frame comprising two spaced vertically-extending bars having their upper ends curved to provide a meeting point midway of the space therebetween, a casting for securing said bars together at their meeting point, said casting carrying the lamp-posi-
- tioning means, and additional means located intermediate the ends of the bars for connecting the bars together against a spreading or closing movement.
11. In a blue-printing apparatus, a supporting-frame comprising two spaced vertically-extending bars braced against a spreading or closing movement, each of said bars having laterally-extending feet to prevent swaying of the frame laterally.
12. In a blue-printing apparatus, a supporting-frame comprising two spaced vertically-extending bars braced against a spreading or closing movement, each of said bars having laterally-extending feet to prevent swaying of the frame laterally, said feet having means for adjusting to inequalities of the supporting surface.

In testimony whereof I have affixed my signature in the presence of two witnesses.

REINHOLD HERMAN.
